UNITED STATES PATENT OFFICE.

FRED ASHWORTH, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

WAX-THREAD-SHOE-SEWING MACHINE.

1,265,986.

Specification of Letters Patent. Patented May 14, 1918.

Application filed June 2, 1916. Serial No. 101,256.

To all whom it may concern:

Be it known that I, FRED ASHWORTH, a citizen of the United States, residing at Beverly, in the county of Essex and State 5 of Massachusetts, have invented certain new and useful Improvements in Wax-Thread-Shoe-Sewing Machines; and I do hereby declare the following to be a full, clear, and exact description of the invention, such as 10 will enable others skilled in the art to which it appertains to make and use the same.

This invention relates to wax thread shoe 15 sewing machines, and more particularly to presser foot lifting mechanism for such machines.

One object of the present invention is to provide a wax thread sewing machine with an improved mechanism by which the presser foot may be unlocked at any time 20 and lifted to allow work to be removed, inserted or adjusted.

A further object of the invention is to provide an improved presser foot lifting mechanism for wax thread sewing machines 25 by which the presser foot will be unlocked from its work-clamping position and lifted to free the work when the machine is stopped.

With these objects in view, the invention 30 consists in the improved presser foot lifting mechanism hereinafter described and set forth in the claims.

The various features of the invention are illustrated in the accompanying drawings, 35 in which Figure 1 is a detail view in side elevation, showing those parts of an outsole sewing machine which are necessary to illustrate the application of the improved presser foot mechanism thereto; and Fig. 2 is a detail view showing the relation of the 40 presser foot lever to the manually operated plunger during the sewing operation.

The sewing machine illustrated in the drawings is an outsole, lock stitch, curved 45 needle machine substantially the same in general construction, arrangement and mode of operation as the machine illustrated and described in my co-pending application, Serial No. 769,566, filed May 24, 1913, on 50 which Patent No. 1,233,539 issued July 17, 1917. This machine is provided with the usual work support 10, awl 12, and presser foot 14. The presser foot 14 is mounted 55 upon the central arm of a three-arm presser

foot lever, 16, 18, 20, pivoted on a stud 21. 55 To actuate the presser foot during the sewing operation an actuating lever 22 is mounted on a movable fulcrum bar 24 and connected by a link 26 with the arm 18 of the presser foot lever. The presser foot is 60 yieldingly pressed against the work by a spring 28, which is connected at one end to the machine frame, and at the other end to a link 30 attached to the lower end of the actuating lever 22. The fulcrum bar 24 is 65 slidably mounted in guides formed in the arms of a yoke 32 which is attached to the machine frame. A nut 34 is mounted on a steep pitch screw formed on the fulcrum bar, and held between the arms of the yoke 70 32. To hold the nut 34 from rotation and thus lock the fulcrum bar from movement at certain times during the operation of the machine, a locking lever 36 is pivoted to the yoke 32 and surrounds the nut 34. A 75 roll 38 is mounted between the arms of the lever 36 and is arranged to be wedged against the bottom of the nut 34 when the locking lever 36 is moved to the right, viewing Fig. 1. The locking lever 36 is connected by a link 40 with a lever 42 which is fixed on a shaft 44 mounted in the machine frame. A lever 46 is fixed on the shaft 44 for simultaneous movement with the lever 42, and is connected to a rod 48 80 which passes through a guide block 50 mounted in the machine frame. A compression spring 52 is mounted on the rod 48 between the guide block 50 and a collar 54 fixed on the rod 48. With this construction 85 the spring 52 normally tends to move the locking lever 36 into a position to lock the fulcrum bar 24 from movement. To move the locking lever into a position to release the locking nut 30 on the fulcrum bar, a 90 lever 56 is loosely mounted on the shaft 44 and carries a setscrew 58 which engages the upper face of the lever 46. A cam lever 60 is loosely mounted upon the shaft 44 and is arranged to have a lost motion connection 100 with the lever 56. The lever 60 has an arcuate section 62 formed on its hub which interlocks with an arcuate section 64 formed on the hub of the lever 56. Shoulders on these sections are shown in engagement at 105 66, Fig. 1. The section 62 has a less circumferential length than the section 64, which permits a movement of the lever 56

relatively to the lever 60, as shown at 68. The upper end of the cam lever 60 carries a roll 70 which engages a path cam on the shaft 72 and is operated to positively 5 rotate the lever 56 in a direction to move the locking lever 36 to the left, viewing Fig. 1, and unlock the fulcrum bar 24.

The lever 22 is operated by a cam lever 74—76 which is pivoted on a stud 78 and 10 connected with the lever 22 by means of a link 80. The arm 74 of the lever 74—76 is provided with a cam roll which engages a path cam on the cam shaft 72. To vary the movements imparted to the presser foot, the 15 link 80 carries a block 82 which is adjustable in an arcuate slot 84 formed in the arm 76 of the lever 74—76.

With the exception of the rigid arm 20 of the presser foot lever the parts so far described are substantially the same in construction and mode of operation as the corresponding parts of the machine of application Serial No. 769,566, above referred to.

To permit the operative to remove or adjust the work, the presser foot mechanism is arranged to be manually unlocked and lifted from the work. The mechanism for actuating the presser foot in this manner comprises an unlocking plunger 86 having its front 25 end extending loosely through an opening 88 in the arm 20 of the presser foot lever which arm, in effect, constitutes a lifting handle by which the presser foot may be raised from the work. The rear end of the plunger 30 86 is connected to the upper end of a lever 90 which is fixed on a pivot shaft 92 journaled in the machine frame. The lower arm of the lever 90 is provided with a cam face comprising two portions 94 and 96, adapted 35 to engage a roll 98 mounted on the end of the lever 56, the construction being the same as in the machine of Patent No. 1,233,539. A spring 100 is connected between the upper 40 arm of the lever 90 and the machine frame and normally tends to hold the plunger 86 in the position illustrated in Fig. 2. When 45 the plunger is in this position a knob 102 threaded on the plunger 86 is removed from the face of the arm 20 of the presser foot 50 lever, and the cam face 94 is in contact with the roll 98. To lift the presser foot from the work, the plunger 86 is pushed toward the rear of the machine and by the time the 55 knob 102 comes into engagement with the lifting handle 20 the face 96 of the cam has acted upon the roll 98 and the fulcrum bar 24 has been unlocked. A continued movement of the plunger 86 will move the cam face 96 over the roll 98 and lift the presser 60 foot 14 off the work. The cam face 96 is substantially concentric with the shaft 92, so that, while the presser foot is being lifted, the fulcrum bar 24 is held in released position. To hold the plunger 86 centered in the 65 opening 88 it is slidably mounted in a sleeve

104 which is attached to an arm 106 fixed on the machine frame. The rear end of the plunger 86 is provided with an adjusting nut 108 by which it may be adjusted to properly time the parts.

When the machine is stopped at the completion of the sewing operation the presser foot is lifted automatically to release the work by mechanism which actuates the lever 90 as in the machine of application Serial No. 769,566. A stopping cam 110 is mounted upon the cam shaft 72 and arranged to coöperate with a cam lever 112. During the normal operation of the machine the cam lever is held out of the path of the cam 110, the face of the cam lever resting against the concentric portion 114 on the cam shaft. When the machine is being stopped, the lever 112 is shifted transversely of the shaft into the path of the cam 110, rides up an inclined face 116 and engages a stop 118. The lever 112 is pinned to a shaft 120 journaled in the machine frame and has a lug 122 which is positioned to engage a lug 124 on a lever 126 loosely mounted on the shaft 120. The lever 126 is connected by a link 128 with the upper arm of a bell crank 130 pivoted on a shaft 132. A headed bolt 134 is mounted at the pivotal connection of the link 128 and bell crank 130, which is engaged by a set screw 136 mounted in a lever 138 pinned to the shaft 92 on which the bell crank 90 is fixed. With this construction, when the cam lever 112 is moved to the right, viewing Fig. 1, in traveling up the inclined face 116 of the cam, the upper end of the lever 138 will be moved to the right. At the same time the bell crank 90 will be oscillated to move the cam face 96 into contact with the roll 98 and simultaneously shift the plunger 86 to lift the presser foot 14.

The invention having been thus described, what is claimed as new is:

1. A shoe sewing machine, having, in combination, a work support, a presser foot lever provided with a lifting handle, a presser foot on said lever, means acting automatically to lock and unlock the presser foot lever during each cycle of operations of the machine, a manually operable plunger mounted to move independently of said lifting handle, and means actuated by said plunger for unlocking the presser foot lever.

2. A shoe sewing machine, having, in combination, a work support, a presser foot lever provided with a lifting handle, a presser foot on said lever, means acting automatically to lock and unlock the presser foot lever during each cycle of operations of the machine, a manually operable plunger mounted to move independently of and into engagement with said lifting handle, and means actuated by said plunger during its independent movement for unlocking the presser foot lever.

3. A shoe sewing machine, having, in combination, a work support, a presser foot lever provided with a lifting handle, a presser foot on said lever, means acting automatically to lock and unlock the presser foot lever during each cycle of operations of the machine, a plunger mounted to move inde-

pendently of and into engagement with said lifting handle, and means acting upon stopping the machine to move said plunger to lift the presser foot lever and to unlock the presser foot lever during the independent movement of the plunger.

FRED ASHWORTH.
